UNITED STATES PATENT OFFICE.

LEE S. CHADWICK, OF EAST CLEVELAND, OHIO, ASSIGNOR TO THE CLEVELAND METAL PRODUCTS COMPANY, OF CLEVELAND, OHIO, A CORPORATION OF OHIO.

DISPENSING-RECEPTACLE.

1,299,914.

Specification of Letters Patent.

Patented Apr. 8, 1919.

Application filed July 20, 1915. Serial No. 40,845.

To all whom it may concern:

Be it known that I, LEE S. CHADWICK, a citizen of the United States, residing at East Cleveland, in the county of Cuyahoga and State of Ohio, have invented a certain new and useful Improvement in Dispensing-Receptacles, of which the following is a full, clear, and exact description, reference being had to the accompanying drawings.

10 This invention relates to an improved dispensing receptacle especially adapted for use in connection with devices of the class shown in my Patent No. 1,137,574, issued April 27, 1915. In the aforesaid patent 15 there is shown a dispensing receptacle which consists of a jar or bottle having, adjacent its neck, an abutment or shoulder, the upper surface whereof is beveled or undercut to coöperate with a supporting member for 20 said receptacle.

It has been found impractical if not impossible to manufacture a bottle or jar having an abutment or a shoulder beveled or undercut as described.

25 It is the object of my present invention, therefore, to provide a dispensing receptacle having an abutment adapting it for use with dispensing devices of the general class disclosed in the aforesaid patent, and that

30 is simple of construction and economical of production by ordinary standard methods of manufacture.

To this end the invention consists in the production of a bottle or jar, preferably of 35 glass, having a peripheral or circumferential bead that is surrounded by an inwardly opening metallic channel member; and the side of the bead that is toward the neck or dispensing end of the bottle or jar may be 40 disposed at substantially right angles to the vertical axis of the bottle or jar, and of a width somewhat greater than the width of the coöperating flange of the channel member.

45 The foregoing is the invention expressed in broad terms. During the following description, however, certain structural details will be introduced for accomplishing the foregoing result in a convenient, economical and facile manner, and which constitute further features of my invention.

In the accompanying drawing which forms a part hereof and wherein similar reference characters designate corresponding 55 parts throughout the several views, Figure

1 is a side elevation and Fig. 2 a plan of a dispensing receptacle constructed in accordance with my present invention; Fig. 3 is a sectional detail through one side of the upper end of the receptacle; Fig. 4 is 60 a detail in perspective of the separated adjacent ends of the channel member or band which surrounds the dispensing receptacle; and Fig. 5 is a horizontal section through the connected ends of the band or channel 65 member.

In the present embodiment of my invention the dispensing receptacle or vessel consists of a cylindrical bottle or jar, preferably of glass, the same being provided with 70 a neck 2 having in the present case, a threaded portion 3 for the application of a suitable valve. In some uses of my dispensing device, however, a valve will be unnecessary, in which case the threaded portion 75 3 may be dispensed with.

Between the body portion of the receptacle or vessel and the neck 2 there is formed a shoulder 5 that is disposed at substantially right angles to the vertical axis of the receptacle. The body portion of the receptacle or vessel has a peripheral groove 6 that is spaced a slight distance from the shoulder 5.

80 A metallic band 10 surrounds the upper end of the body portion of the receptacle, and the same has its upper and lower edges curled over and inward to produce ridges or flanges 11 and 12, respectively. The band thus formed constitutes, in effect, an 85 inwardly opening channel member which embraces the bead 14, between the shoulder 5 and the groove 6. The ridge or flange 12 occupies the groove 6, while the ridge or flange 11 overlies and contacts with the shoulder 5. The band is preferably made of a length substantially equal to the circumference of the receptacle or vessel, and one of its ends is provided with a tongue 15, and the other with an aperture 16 through 90 which said tongue is arranged to extend when the band is drawn about the receptacle. After passing through the aperture 16, the tongue 15 is bent abruptly back over and upon that end of the band from which it 95 projects, and the free end of the tongue is fastened to said end of the band preferably by applying a quantity of solder 17 thereto.

To relieve the tongue 15 of lateral strain and to assist in holding the adjacent ends 110

of the band in true alinement, I may employ short wire dowel pins 18 that are inserted in the opposed ends of the curled over edges or flanges 11 and 12 of the band.

5 While I have described the dispensing receptacle as cylindrical, it is obvious that the same may be rectangular in plan, or of any other desired shape, without departing from the spirit of my invention. Also, the band or channel member 10 may be modified by altering the form of the ridges or flanges 11 and 12; and the dowel pins 18 may be discarded without materially decreasing the efficiency of the device.

10 Having thus described my invention, what I claim is:—

15 A dispensing receptacle designed to be

supported in inverted position by a suitable supporting structure and comprising a body portion having a peripheral bead and a 20 neck projecting therebeyond, and a metallic channel member having its open side disposed inwardly and surrounding the body portion and embracing the bead, the side of the channel member toward the neck receding inward away from the neck thereby to produce a confined supporting shoulder or ledge.

25 In testimony whereof, I hereunto affix my signature in the presence of two witnesses. 30

LEE S. CHADWICK.

Witnesses:

W. E. SHEPPARD,
OPHELIA A. SMITH.
